CENTERING SUPPORT

Leon P. Morey, Rochester, N. Y., assignor to Eastman Kodak Company, Rochester, N. Y., a corporation of New Jersey

Application February 14, 1946, Serial No. 647,587

3 Claims. (Cl. 242—46.6)

1

This invention relates to centering support, and particularly to a convenient arrangement of parts designed for readily and easily placing either a loaded or empty core on, or removing such a core from, a web unwinding or winding spindle, and automatically causing an inter-engagement or disengagement between the driving head of said spindle and the core, without the necessity of careful and accurate placement of the latter.

In the manufacture of paper, photographic film, fabrics and other continuous strip material, it is customary to wind several thousand feet of strip on one core or roll center. Such cores are conveniently made of drawn or rolled tubing. When such a core has a long web of film base, for instance, wound upon it, the total weight may exceed four hundred pounds, and this of course necessitates handling and lifting the roll from a wind-up or onto a reel-off mechanism by means of power, such as an electric or pneumatic hoist. Obviously, extremely close control of such a hoist in order to align exactly the core with a driving member or on dead centers is impractical.

Guiding the ends of such a roll onto supporting and driving centers is quite difficult. Not only is there an ever present danger that an operator's fingers may be injured, but the ends of the tubular cores are frequently distorted and centering supports damaged. Therefore, some self-guiding means, capable of overcoming such misalignment, is desirable. If such means are also resilient as well as having an automatic directing function, the roll may be placed on supports with minimum loss of time. The present invention contemplates the provision of a structure fulfilling not only the above conditions, but also providing a driving engagement for a core.

In the drawings, in which like reference numerals are applied to corresponding parts in the several views,

Fig. 1 is a fragmentary side elevation of one end of a tubular roll core as it appears when in place and in engagement with the resilient centering supports aforementioned;

Fig. 2 is an end view as the parts would appear in a section taken on line 2—2 of Fig. 1;

Fig. 3 is an enlarged fragmentary longitudinal section on line 3—3 of Fig. 2, the core and the resilient parts being out of engagement;

Fig. 4 is a similar section showing the core supported in operative position; and

Fig. 5 is a fragmentary plan of a detail.

Referring first to Figs. 1 and 4, 10 represents a generally cylindrical head which may be remova-

bly attached to a shaft 11 by a stud 12, and centered thereon by having a circular recess 13 fitting closely a tapered boss 14. The shaft 11 may be supported in suitable bearings 15, one of which, not shown, with a stub shaft, is adapted for longitudinal movement to serve as a dead end or tailstock at the other end of the core while the one shown may be considered as a driven head.

The part 10 in the present showing has a deep annular recess 16 between the main central portion and a marginal flange 17. A shoulder 18 provides a stop and locating element for a ring 19. This ring and a second ring 20 are centered on a reduced hub portion 10' of the head 10. Between the rings 19 and 20 a series of substantially U-shaped springs 21 and 22 are supported on pins or rivets 23 which are forced into close-fitting holes in the ring 20. The springs 22 serve as reenforcing members for the springs 21 and take up part of the load when the springs 21 are slightly flexed. Both sets of springs are fabricated in such manner that when they are pressed within the annular flange 17 they will be under stress and therefore "pre-loaded" to the extent of several pounds each.

As shown in Fig. 2, these pairs of springs are located radially with their outer portions in substantially edge-to-edge contact all around the rings 19 and 20. A third ring 24 is provided to shield the inwardly-turned free ends 25 of the springs, which, between these ends and their outer straight portions, include curved portions 26. It is the latter which provide the points of support for the core C, a part of one end of which is shown in Fig. 3 as it appears when being moved into operative relation with the head 10. The plate 24 is held in place to serve as a retainer for the spring-and-ring assembly 19, 20, 21, 22, by studs 27 that pass through the hub portion of the head, and are placed and set up before the head is attached to shaft 11 by the center stud 12. Spacers or lugs 17' projecting inwardly from the flange 17 lie between adjacent springs, the latter being narrowed to accommodate the lugs, as indicated in Fig. 5. The whole assembly is driven from shaft 11 by a pin P which engages the head 10 at a suitable distance from the center thereof, as shown in Fig. 4.

The core C shown in the drawings is of comparatively thin tubing. At one end is an inwardly depressed forming 28 that is slightly less in width in a circumferential direction than one of the springs 21, 22, at their outer portions 26. When the core is pushed toward the flange 17 of head 10, or toward the right in Fig. 3, as

indicated by the arrow, the forming 28 will depress whichever spring it happens to be aligned with. As the core moves further, its entire inner periphery or edge 29 engages all the other springs, and even if it is not concentric with the head 10, it will quickly become so because all the springs are of equal strength and immediately tend to center the core, the entire set acting as a conical guide to align the core C with the flange 17.

The forming 28 may actually depress two springs to the position B in Fig. 4. However, as soon as the head 10 is rotated, the forming will slip past one spring and will be caught between two as shown in Fig. 2, thus serving as a driving key for the core, and transmitting to the latter the rotary motion of the driven head 10 and shaft 11. This automatic engagement obviates the necessity of an operator placing his hand at the end of the roll to guide a core into place.

As the web of film or other material builds up on the core C, and the whole becomes increasingly heavier, it may sag slightly out of concentricity with shaft 11 but the preloaded condition of the springs limits this to a few thousandths of an inch. At any given moment the upper 6 or 7 springs (as viewed in Fig. 2) will be carrying the entire weight of one end of the core and material, the rest of the springs merely being in the normal preloaded condition. As each spring moves up toward the top, it picks up more of the load, and as it passes beyond the top center, its load decreases. The springs within approximately 45° either way from top center are always carrying the load and the others serve merely as centering guides, remaining in the position of Fig. 3.

The tailstock, not shown, may have the same construction as has just been described, except that its shaft will not be driven, and the spring-carrying head may be moved axially to enter the other end of the core to serve as a dead-end center.

The preferred form of the invention, as above described, has been found extremely practical and useful, for time saving, safe operation, and ruggedness. However, the precise structure shown may be modified in design as required, within the scope of the following claims.

What I claim is:

1. A core support for tubular cores of the type having one or more protuberances, said support comprising a plurality of springs between any two alternate units of which said protuberances may be inserted to serve as means for driving

said core, a rotatable head, a ring member mounted on said head and carrying said springs with the latter disposed radially and with their free ends recurved toward the axis of said head, whereby portions of the faces of said springs constitute a concentric resilient seat for said core and parts of the edges of said springs constitute driving means therefor.

2. A centering support for tubular cores which have one or more lugs projecting inwardly from the shell of said core, comprising, in combination, a plurality of substantially U-shaped spring members mounted on a central disc and having their ends recurved inwardly; an annular driven head provided with spring spacers and partly surrounding said springs; a second central disc connected with said head and extending over the free ends of the springs, said springs thereby constituting a resilient core support wherein any one of said springs is yieldable to permit the core lugs to enter between alternate springs to provide combined driving and supporting means for the core.

3. A centering support adapted to receive and to drive tubular cores which have inwardly projecting lugs, or the like, constituting driving keys therefor, comprising, in combination, a series of substantially U-shaped springs mounted on a disc; a second disc attached to the latter and extending over the recurved inwardly directed free ends of the springs; a driving head connected with one of the discs and having an extended periphery partially enclosing said springs and so arranged that when a tubular core approaches said head, the springs constitute both a yielding centering support and a driving member therefor, any of said springs being sufficiently resilient to yield and thereby to permit a core lug to enter between springs so that the core may be driven thereby.
